UNITED STATES PATENT OFFICE.

WILLIAM T. ANDERSON, OF BROOKLYN, NEW YORK.

BATHING-SUIT.

No. 839,699.

Specification of Letters Patent.

Patented Dec. 25, 1906.

Application filed January 10, 1906. Serial No. 285,442.

To all whom it may concern:

Be it known that I, WILLIAM T. ANDERSON, a citizen of the United States of America, residing at Brooklyn, in the county of Kings and State of New York, have invented new and useful Improvements in Bathing-Suits, of which the following is a specification.

This invention relates to bathing or swimming suits the object of the invention being to provide a simple, practicable, and comfortable bathing-suit especially adapted to the needs of swimmers and divers, the two parts or sections of which the suit is composed being so constructed and provided with fastening devices that any separation between the two parts of the bathing-suit will be prevented and the suit as a whole comfortably and securely held in place relatively to each other and upon the person of the wearer.

With the above and other objects in view the invention consists in the novel construction, combination, and arrangement of parts hereinafter more fully described, illustrated, and claimed.

In the accompanying drawings, Figure 1 is a front elevation of a bathing-suit embodying the present invention. Fig. 2 is a side elevation of the shirt or jersey. Fig. 3 is a front view of the upper portion of the trunks or trousers. Fig. 4 is a rear elevation of the same. Fig. 5 is an enlarged view in elevation of the lower portion of the front of the shirt or jersey, showing the securing-strap and stays.

Referring to the drawings, 1 designates the shirt or "jersey," as it is commonly called, the same being provided with the usual neck-opening 2 and arm-holes 3, while 4 designates the trunks or trousers provided with the usual leg portions 5, which may be of any desired length, the several openings in the shirt and trunks being faced or bound in any convenient manner.

In carrying out the present invention the side portions of the jersey or shirt are cut away or rounded out, as shown at 6, to pass comfortably over the hips, thus leaving a centrally depending and rounded front portion 7, which extends downward well over the abdomen. Connected centrally to the down-

wardly-extending front portion 7 of the shirt is a strap or band 8, which is secured permanently at 9 to the front portion of the shirt, as shown in Fig. 5, and provided at its opposite end with a buttonhole 10 or its equivalent, whereby the strap may be passed between the legs and secured to a complementary fastening device, such as a button 11, at the back of the shirt or jersey and adjacent to the lower edge portion thereof, as shown in Fig. 2. This strap 8 may be of any desired width and is further secured by means of angularly-extending stays or additional straps 12, which extend from a common point 13 on the strap 10 upward divergently and are secured permanently at the points 14 to the front of the jersey or shirt at points equidistant from the point of attachment 9 of the main securing-strap 8. Between the points 9 and 10 sufficient fullness is allowed in the strap 8, as shown in Fig. 5, to allow for the rotundity of the figure.

Extending around the upper edge of the trunks or trousers 4 is a belt or waistband 15. This belt or band is secured at the points 16 permanently to the trunks, the points 16 being located about midway between the front center of the garment and the side line directly over the hips, and from the points 16 around the back of the trunks or trousers the belt is secured thereto by parallel rows of stitches, as shown at 17. The front end portions 18 of the belt are left free and provided with complementary fasteners 19 and 20, such as a buckle and perforations, whereby the belt may be adjusted tightly around the wearer. The shirt or jersey is further provided at opposite sides with buttons or other forms of fastening devices 21, while the side portions of the trousers just over the hips are provided with complementary fasteners to engage the devices 21 for supporting the trousers at the sides. The back of the trunks is preferably cut somewhat higher than the front to prevent the trousers from sagging in the rear.

Any suitable fastening devices of well-known or familiar form may be employed for securing the free ends of the belt 15 and also for securing the strap 8 and for fastening the side portions of the trousers to the shirt or jersey.

I claim—

The herein-described bathing-shirt having a downwardly-extending front flap, a strap secured at one end to said flap to pass between the legs of the wearer, said strap being detachably secured to the back of the shirt, oblique stays connected to said flap at opposite sides of said strap, said stays being brought together and secured to said strap

intermediate its ends, and a pair of trunks to detachably connected to said shirt, essentially as described.

In testimony whereof I affix my signature in presence of two witnesses.

WILLIAM T. ANDERSON.
